PERFORATED RECORD SENSING DEVICE

Reynold B. Johnson, Binghamton, N. Y., assignor to International Business Machines Corporation, New York, N. Y., a corporation of New York

Application August 14, 1947, Serial No. 768,559

7 Claims. (Cl. 235—61.11)

1

This invention relates to punching or perforating machines and more particularly to machines of the type in which the punching may be controlled manually or by a previously punched card.

The invention is directed to improvements in the type of machine disclosed in F. Lee et al. Patent 1,976,618, granted October 9, 1934 but it is understood that the present improvements may be applied to other forms of machines with equally beneficial results and that the present showing is to be considered illustrative rather than restrictive.

The principal object of the invention is to provide a new form of record card sensing or analyzing mechanism which is adapted to sense the perforations of a master or pattern card to control the actuation of the punching mechanism. In the machine to which the invention is applied, the master or pattern card is placed in a carriage which reciprocates the card to pass a line of sensing elements, and since the reciprocations are numerous it is desirable to provide a sensing device which is out of contact with the card surface during the periods when the card is in motion to thereby obviate wear of the card surface and possible damage to the sensing elements.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a top plan view of the punching and duplicating machine embodying the present invention.

Fig. 2 is an enlarged section taken on the lines 2—2 of Fig. 1 showing the sensing elements and their operating devices.

Fig. 3 is a portion of an end elevation of parts in Fig. 2 looking in the direction of the lines 3—3.

Fig. 4 is a wiring diagram of the electric circuits of the machine showing the manner in which the electrical elements of the invention are incorporated therein.

The operation of the machine to which the invention is applied will first be briefly explained with reference to Fig. 1 and thereafter the manner in which the invention is applied thereto will be set forth. Reference may be had to Patent 1,976,618 referred to, for a more detailed explanation of the main machine, which is commercially known as the IBM motor driven duplicating punch. To facilitate cross reference the same reference characters will be employed as in the patent to like elements and the elements of the invention will be distinguished by the suffix *a*.

2

The machine is arranged for convenient right hand operation by a handle or finger piece 2' which, when shifted toward the left, as viewed in Fig. 1, either manually or by the power mechanism of the patent will cause picker 2 to advance a blank card from the bottom of stack 4 to the punching position beneath a row of punches 5. Thru the usual connections comprising gear 16, shaft 23, and gear 24, rack 25 is driven to the right carrying with it blank card carriage 6 comprising a left and right guide, and pattern card carriage 8 comprising also a left and right guide. Blank card 3 and pattern card 10 are shown in their respective carriage which hold them in columnar alignment and with rack 25 in its right hand position the left hand portion of card 3 is beneath punches 5.

Manipulation of keys 9 or energization of magnets 60 will activate the punches and for each actuation, the usual escapement devices are operated to advance the rack 25 and carriage 6 and 8 one card column or step to the left until the cards reach the position of Fig. 1. From this position card 3 is then automatically ejected toward the left and the carriages return to the right where carriage 6 receives a new blank card.

Pattern card 10, however, remains in its carriage so that it returns to the right and then accompanies the next blank card on its journey to the left. This card 10 is provided with perforations in selected columns which it is desired to duplicate in corresponding columns of each card 3. To this end, a row or line of sensing pins 10a (see Fig. 2) is located in line with punches 5 and the operation is such that when a column of card 10 is beneath pins 10a, the corresponding column of card 3 is beneath the punches 5. The pins 10a, at such time will sense the column of card 10 and if a perforation is found therein, a circuit will be completed to energize an appropriate duplicating magnet 60 to effect punching of a corresponding hole in the column of card 3.

There is a pin 10a, provided for each of the usual twelve punch positions of the pattern card. Each of the pins comprises a sleeve 11a in the lower end of which is inserted a tightly wound spring 12a. Within the lower end of spring 12a is the sensing point 13a. This construction enables a slight flexure of the lower extremity so that if the card should strike against the side of point 13a, it will yield and snap back in vertical alignment when released.

A hook 14a is secured in the upper end of sleeve 11a and engages in an opening of an insulating eyelet 15b in the free end of an armature link 15a which is pivoted at 16a to a metallic block 17a.

Sleeves 11a are guided thru an angle plate 18a and are configured with extensions 19a at their

upper ends to cooperate with springs 20a, normally urging the pins 10a upwardly to hold link 15a against an insulating stop 21a. Each hook 14a is insulated from its link 15a and a separate block 17a is provided for each link, mounted on an insulating bar 22a. Thus each link 15a and related block 17a is electrically insulated from the others and from the machine framework.

Extending across beneath all twelve links 15a is the metallic core 23a of a winding 24a. The 10 core is fastened to a bracket 25a which is also insulated from the machine framework.

It is thus apparent that upon energization of winding 24a, all the armature links 15a will be urged in a counterclockwise direction (Fig. 2) about their pivots 16a and all pins 10a will be urged downwardly against card 10. In positions where a hole occurs the pin's point 13a will pass thru the hole and allow the link to rock sufficiently to contact core 23a. In position where there is no hole, the surface of the card will intercept the pin movement and prevent contact of link 15a and core 23a.

The causes and consequences of these actions may best be explained by reference to the wiring diagram of Fig. 4 wherein the elements are identified by the same reference characters as in the patent to which reference may be had for details of operation.

Briefly the so called floating cam contact 128 30 closes coincidently with the presentation of each card column to the sensing pins 10a and punches 5 and remain closed until an escapement is effected to advance the card to the next column. When contacts 128 close, a circuit is completed 35 from line 134, contacts 136, 135, 187, and 128 to winding 24a and to line 133.

This will cause attraction of all links 15a, but if the card column at the pins 10a is unperforated, all links 15a are prevented from rocking to their limit positions. If a perforation is encountered in some positions, the related pin 10a will descend its full extent and the related link 15a will contact the common core 23a to complete a parallel circuit extending from contacts 45 128 to core 23a, link 15a, and related duplicating magnet 60 to line 133.

Operation of magnet 60 will, as usual, punch a hole in card 3 and as an incident thereto cause opening of contacts 128 before the card carriages are escaped to the next column. Therefore, the circuits traced are broken, to enable retracting of pins 10a, which will occur before the cards move, so that during such movement the pins are out of engagement with the card.

It is thus seen that with the device of the invention, pins 10a are magnetically urged into sensing position for each card column sensed and when a hole is encountered, a circuit is completed thru the magnet core to effect duplicate punching. Where no hole is encountered, the second circuit is of course, not completed and carriage advance occurs under key control, which as usual, also effects opening of contacts 128 to insure that with the cards in motion, pins 10a 65 are out of engagement therewith.

While there have been shown and described and pointed out the fundamental novel features of the invention as applied to a preferred embodiment, it will be understood that various omissions and substitutions and changes in the form

and details of the device illustrated and in its operation may be made by those skilled in the art without departing from the spirit of the invention. It is the intention, therefore, to be limited only as indicated by the scope of the following claims.

What is claimed is:

1. In a machine having a card sensing station, and a card carriage movable step by step to present successive columns of a card to said station, in combination with a set of sensing pins at said station, normally biased out of contact with the card, electromagnetic means for moving the pins into engagement with the card, control means for effecting advance of the carriage and means controlled thereby for repeatedly energizing the electromagnetic means, once for each card column presented to said station.

2. In a machine having a card sensing station, a card carriage and devices for advancing the carriage step by step to present a succession of card columns to the station, in combination with sensing devices at the station, normally biased out of engagement with the card and means controlled by said advancing devices to cause the sensing devices to descend into engagement with the card at each step while the card is at rest and to be in raised position while the card is in motion.

3. In a machine of the class described, a card sensing device comprising a plurality of sensing pins located adjacent a card to be sensed and normally biased out of engagement therewith; a plurality of magnet armatures one for each pin, connected to said pins for moving the same into sensing position, a magnet common to all the armatures and means for energizing the magnet to cause the pins to move concurrently into sensing position, engagement of a pin in a hole in the card enabling the pin to move a predetermined extent and engagement of a pin with an imperforate part of the card limiting the movement of the pin to a lesser extent.

4. The invention set forth in claim 3 in which a contact device is provided for each pin, and a circuit connection including said contact devices, the movement of any pin to its greater predetermined extent causing closure of said contact device to complete the circuit connection.

5. The invention set forth in claim 3 in which the card contacting extremity of each sensing pin is constructed to enable flexure of the contact end out of a straight line, and spring means is provided to bias the end in a straight line.

6. In a machine of the class described, a card sensing pin, located adjacent a card to be sensed, and normally biased out of engagement therewith, a magnet armature connected to the pin for moving the same into sensing position, a magnet for operating the armature and means for energizing the magnet to cause the pin to contact the card.

7. The invention set forth in claim 6 in which the armature contacts the magnet core when the actuated pin encounters a hole in the card, and a signal circuit, said core and armature constituting a circuit closing device in said circuit to close the same.
